MACHINE FOR FORMING EARTHEN AND STONE WARE.

No. 325,911.

Patented Sept. 8, 1885.

UNITED STATES PATENT OFFICE.

DENISON S. CHESEBRO, OF GEDDES, NEW YORK.

MACHINE FOR FORMING EARTHEN AND STONE WARE.

SPECIFICATION forming part of Letters Patent No. 325,911, dated September 8, 1885.

Application filed June 16, 1885. (No model.)

To all whom it may concern:

Be it known that I, DENISON S. CHESEBRO, of Geddes, in the county of Onondaga, in the State of New York, have invented new and useful Improvements in Machines for Forming Earthen and Stone Ware, of which the following, taken in connection with the accompanying drawings, is a full, clear, and exact description:

10 The object of this invention is to manufacture hollow ware from tempered clay or other plastic material in an expeditious and a perfect workman-like manner, and at a minimum expenditure of manual labor.

15 The invention consists in a novel construction and organization of mechanisms constituting a machine for accomplishing the aforesaid object, as hereinafter fully described, and specifically set forth in the claims.

20 In the accompanying drawings, Fig. I is a side elevation of my invention in position for forming the ware. Fig. II is a side elevation showing the invention in position for finishing the interior of the ware. Fig. III is a front elevation of the machine in position for finishing the exterior of the ware. Fig. IV is a vertical section taken on line *x* *x*, Fig. I. Fig. V is an enlarged vertical section of the core around which the ware is formed, and 25 the case which embraces and holds the ware while the core with its cutters cut out and trim the interior of the ware. Fig. VI is a horizontal transverse section on line *y* *y*, Fig. V, and Fig. VII is an enlarged detached plan 30 view of the adjustable latch.

Similar letters of reference indicate corresponding parts.

A represents the main supporting-frame of the machine, consisting of a stout iron stand- 40 ard, on the front of the lower portion of which is journaled the upright shaft *n* of the turn-table *T*.

The requisite rotary motion is imparted to the turn-table either by a pulley, *M*, attached to the shaft *n* and a belt or friction wheel running on said pulley or by any other suitable and well-known means.

Central over the turn-table *T* is a core, *C*, pivoted independently of said table on the 45 lower end of a shaft, *a*, which is journaled on a slide, *H*, moving in a vertical guide, *G*, on

the upper front portion of the frame *A*. Said slide *H* with the core *C* is counterpoised by a weight, *K*, connected with the slide by cords or chains *o* running over pulleys *I* *I*, pivoted on the upper end of the frame *A*. The core *C* has its sides perforated and provided with circumferential flanges *p* *p*, for the purpose hereinafter explained.

To the lower end of the shaft *a* is rigidly attached a cutter, *b*, which is extended across the bottom of the core *C*.

Above the core is a yoke, *c*, rigidly attached to the shaft *a*, and to the ends of said yoke and of the cutter *b* are attached vertical 65 cutters *e* *e*, which are held contiguous to the flanges *p* *p* of the core and stand clear of the perforated body of the same, so that by sweeping the aforesaid cutters around the core a body of clay will remain on the perforated 70 portion of the core. The attachment of the cutters *e* *e* to the yoke *c* I make adjustable by connecting said cutters with hangers *d* *d*, having screw-threaded shanks passing through the yoke, and provided with nuts by which to 75 raise the hangers so as to impart the requisite tension to the cutters *e* *e*. The cutter *b*, on the lower end of the shaft *a*, and a collar, *r*, on said shaft at the upper end of the journal of the core, confine said core longitudinally on 80 the shaft, and said shaft is confined longitudinally on the slide *H*, so that by raising and lowering the latter the core *C* is raised and lowered correspondingly.

On the slide *H* is hinged a latch, *s*, provided with a stud-pin, *i*, by which it engages with a hole in the frame *A*, and thereby retains the said slide and core *C* in its required position.

Since the position of the core over the turn-table varies according to the thickness of the bottom of the ware to be formed, I make the latch adjustable by providing it with a longitudinal slot for the reception of the stud-pin *i*, which is screw-threaded, and clamped in 90 position by a nut on said stud-pin at the back of the latch, as illustrated in Fig. VII of the drawings. By shifting the stud-pin *i* in the slot of the latch the slide *H* can be locked to retain the core *C* at a greater or less elevation above the turn-table.

The shaft *a* is provided with a square or

angular rigid collar, *t*, and on the slide *H* is hinged a clutch, *u*, which is adapted to interlock with the collar *t* and thereby restrain the rotation of the shaft *a*.

5 At the side or back of the turn-table *T* is a radial guide, *N*, on the frame *A*, and in said guide moves a slide, *L*, to the end of which, adjacent to the turn-table, is attached a tangential guide, *g*, and back of said guide are two vertical rollers *h h*, pivoted on the slide *L*.

On the guide *g* is mounted removably a breast, *B*, upon which to place the material, which is to form the body or vertical sides of the ware, the rollers *h h* serving to sustain said breast vertically while sliding it along on the guide *g*, and pressing the material onto the core *C*, as hereinafter described. By means of a lever, *R*, pivoted to the base of the frame *A* and to the slide *L*, the latter is moved toward and from the turn-table.

The latch *l* is pivoted on the frame *A*, and has a lug, *i*, adjustably connected to it, in the same manner as the attachment of the lug *i* of the latch *s*, hereinbefore described. By means of this latch *l* the slide *L* is retained in its required position for pressing the material onto the core, as aforesaid.

On the slide *L* is a guide, *S*, in which moves a slide, *P*, and to the end of the latter nearest the turn-table is attached a scraping-plate, *m*, the edge of which is shaped according to the vertical outline of the exterior of the ware to be formed on the turn-table.

35 *D* represents a metallic case composed of detachable sections, and having its interior shaped to coincide and fit closely to the exterior of the ware to be formed. It is lined with plaster-of-paris to prevent the plastic material from adhering to it. A ring, *E*, clamped de-

40 tachably around the exterior of said case, serves to hold it intact when required.

The operation of my invention is as follows: The turn-table *T* being set in rotary motion, and the core *C* elevated from the table 45 as illustrated in Fig. II of the drawings, the operator places upon the turn-table a disk of material of fully the thickness to be given to the bottom of the ware to be formed. Then the clutch *u* is thrown out of engagement with 50 the collar *t*, and the core *C* is drawn down onto the aforesaid disk of material and retained there by the engagement of the latch *s* with the frame *A*. The lower cutter, *b*, being pressed into the disk of material, causes 55 the core to rotate with the turn-table. Then an elongated disk of material of sufficient length to reach around the core *C* is placed on the breast *B*, which is removed from the guide *g* and sprinkled with either fine sand or 60 ground burned clay to prevent the material from adhering to it. Then the breast *B*, with the material resting thereon, is mounted endwise on the guide *g* and moved along on the same, the slide *L* having previously been set 65 in position to hold the breast so as to press the material onto the core *C* and against the

bottom disk of material. During the rotation of the turn-table and core and the movement of the breast *B* along the guide *g* the material takes hold in the perforations of the core, and is thereby drawn away from the breast *B* and made to adhere to the core to form the body of the ware, as represented by dotted lines in Fig. I of the drawings. The breast *B* being withdrawn, the slide *P* is next moved toward 75 the turn-table to bring the scraper *m* to operate on the exterior of the body of material enveloping the core, as represented by dotted lines in Fig. I of the drawings, said scraper imparting the final shape to the exterior of 80 the ware in process of being formed. Both slides *L* and *P* are then retracted from the turn-table, and the case *D* is placed around the body formed as aforesaid, and the clamping-ring applied to the case. Then the clutch 85 *u* is thrown into engagement with the collar *t*, to prevent rotation of the shaft *a*, thereby holding the cutters *e e* and *b* stationary while the turn-table with the plastic body is rotated, the case *D* serving to sustain said body laterally while the aforesaid cutters cut the core 90 loose from the enveloping material and trim the interior of the plastic body. Then the core *C* is raised out of the said body, and the latter is removed from the turn-table by means 95 of the inclosing-case *D*. In cutting the core loose as aforesaid a layer of material is retained on the perforated portion of the core, which layer serves as a facing for the adhesion of the disks of material applied thereto 100 by the breast *B* during the successive operations of the machine.

Having described my invention, what I claim as new, and desire to secure by Letters Patent, is—

105

1. A machine for forming hollow ware from plastic material, comprising a turn-table upon which to revolve the material, and a pivoted core arranged over the center of the turn-table to revolve with the same and receive 110 around its exterior the material for the body of the ware and sustain said material while turning it to shape externally, substantially as set forth.

2. In combination with the turn-table and pivoted core, a breast arranged movable at the side of the core to apply thereto the material carried on said breast, substantially as described.

3. In combination with the turn-table and pivoted core, a tangential guide at the side of the turn-table, and a breast mounted movably on said guide to apply to the core the material carried on said breast, substantially as set forth and shown.

4. In combination with the turn-table and pivoted core, a tangential guide at the side of the turn-table, the breast mounted movably on said guide, and vertical rollers back of the guide to sustain the breast in its vertical position, substantially as described and shown.

5. In combination with the turn-table and

125

130

core, a cutter extended across the bottom of the core for forming the interior bottom of the ware, substantially as specified.

6. In combination with the turn-table and core, cutters arranged at the sides of the core to cut the same loose from the enveloping material, substantially as set forth.

7. In combination with the turn-table, a vertical shaft arranged over the center of the turn-table, the core pivoted on said shaft, a yoke fastened to said shaft above the core, a horizontal cutter extended across the bottom of the core and attached to the aforesaid shaft, cutters at the outside of the core attached to the ends of the horizontal cutter and yoke, and a clutch for restraining the rotation of the vertical shaft, substantially as described and shown.

8. In combination with the turn-table, a vertical guide, a slide in said guide, and the core arranged over the center of the turn-table and carried by the aforesaid slide, substantially as and for the purpose specified.

9. In combination with the turn-table, the core C, having perforations in its sides, substantially as and for the purpose set forth.

10. In combination with the turn-table, the vertical shaft *a*, arranged central over the turn-table, the core C, pivoted on said shaft, the cutter *b*, rigidly secured to the lower end of the shaft, the yoke *e*, rigidly attached to the shaft above the core, hangers *d d*, having screw-threaded shanks extending through the ends of the yoke, adjusting-nuts on said shanks, and the cutters *e e*, attached to the ends of the cutter *b* and to the hangers *d d*, substantially as described and shown.

11. In combination with the turn-table, the core C, pivoted central over said table and provided with circumferential flanges and perforations, and the straight cutters *e e* at the outside of said core, contiguous to the flanges thereof and clear of the perforated body of the same, whereby a body of material is maintained on the core, substantially as set forth.

12. In combination with the turn-table, the vertical guide G, the slide H, pulleys II, counter-weight K, connected with the slide by cords or chains running over the pulleys, the vertical shaft *a*, journaled on the slide, the angular collar *f* on the shaft, the clutch connected mov-

ably to the slide, the core C, pivoted on the shaft *a*, the cutter *b* and yoke *c*, rigidly attached to the shaft, respectively, beneath and above the core, and the cutters *e e*, attached to the ends of the cutter *b* and yoke *c*, substantially as described and shown. 55

13. In combination with the turn-table and core, a slide arranged radially at the side of the turn-table, a tangential guide attached to the slide, and a breast mounted movably on said guide to apply to the core the material for the body of the ware to be formed, substantially as described and shown. 60

14. In combination with the turn-table and core C, the slide L, arranged radially at the side of the turn-table, the tangential guide *g*, attached to the slide, the breast B, mounted on the guide, and the rollers *h h*, pivoted on the slide back of the guide *g*, substantially as described and shown. 65

15. In combination with the turn-table and core, the frame A, provided with a radial guide, N, the slide L, provided with the locking eye *i*, the guide *g*, attached to said slide, the breast B, mounted on the guide *g*, rollers *h h*, pivoted on the slide back of guide *g*, and the latch *l*, having the lug *l'* adjustably connected thereto, substantially as and for the purpose set forth. 75

16. In combination with the turn-table and core, the slide P, and the scraper *m*, attached to said slide, substantially as and for the purpose specified. 80

17. In combination with the turn-table, the core C, pivoted over the turn-table independently thereof, cutters *b e e* across the bottom and up the sides of the core, and the case D, mounted removably on the turn-table and embracing the material surrounding the core, substantially as and for the purpose set forth. 85

18. In combination with the turn-table, the core C, carried on a vertically-movable shaft, *a*, cutters *b e e* underneath and at the sides of the core, and the case D, mounted removably on the turn-table and embracing the material surrounding the core, substantially as and for the purpose set forth. 90
